DESIGN FOR A METAL BRACKET CLOTHES HANGER

Thomas Norman Badger, Berkeley, Calif.

Application June 28, 1943, Serial No. 110,548

Term of patent 14 years

To all whom it may concern:

Be it known that I, Thomas Norman Badger, a citizen of the United States, residing at Berkeley, in the county of Alameda and State of California, have invented a new, original, and ornamental Design for a Metal Bracket Clothes Hanger, of which the following is a specification, reference being had to the accompanying drawing, forming part thereof.

Fig. 1 is a side elevational view of a metal bracket clothes hanger, showing my new design; and

Fig. 2 is a sectional view on line 2—2 of Fig. 1.
I claim:

The ornamental design for a metal bracket clothes hanger, as shown.

THOMAS NORMAN BADGER,
